VECTOR AND TRIGONOMETRIC STATIC-
BALANCE COMPUTER

Marlene McCoy, 5209 N. University Ave., Peoria, Ill.
Filed Mar. 28, 1963, Ser. No. 268,827
5 Claims. (Cl. 235—61)

This invention relates to analog computers, and, more particularly, to devices for the rapid and ready summation of vectors.

The study of vectors has been one of the most exasperating for many students. This is particularly true when several vectors are to be resolved into their components or are to be added. Since vectors are abstractions, they are apparently not readily understood by many individuals. Even the use of instruction aids has not fully solved this problem. And vectors are important in many activities and in many fields of endeavor. For this reason, computers have been devised to calculate and analyze vectors. Generally these computers are complex and cumbersome to use, and their value is questionable.

This invention provides a new and simple device for the study and the computation of vector problems and trigonometric problems.

It is an object of this invention to provide a new and improved device for the study of vectors.

It is another object of this invention to provide a new and improved device for the computation of vector problems.

It is a further object of this invention to provide a new and improved device for the study and computation of trigonometric problems.

Other objects and advantages of this invention will become apparent as the following description proceeds, which description should be considered together with the accompanying drawings in which:

FIG. 1 is a sectional view of the computer of this invention;

FIG. 2 is a plan view of the computer of FIG. 1;

FIG. 3 is an illustration of a trigonometric problem to be solved by the computer of this invention;

FIG. 4 is a plan view of the chart of FIG. 2 showing the solution of the problem of FIG. 3;

FIG. 5 is a diagram of a vector problem to be solved by the computer of this invention; and

FIG. 6 is a plan view of the chart of FIG. 2 showing the solution of the problem of FIG. 5.

Referring now to the drawings in detail, and in particular to FIGS. 1 and 2, the reference character 11 designates a housing which may be made of any suitable construction material such as wood, metal, synthetic resin, and the like. The housing 11 is generally circular in shape and shallow and contains a vertical support 12 in its center. A pivot pin 13 is vertically mounted in the top of the support 12 to fit in a conical bearing 14 in the center of a circular disc 15. Immediately above the bearing 14 and centered on the top surface of the disc 15 is a circular bubble level. The housing 11 comprises a rim 17 at its top surface, which is otherwise open. An annular disc 19 carrying knob 18 is supported on the rim 17 to be readily rotated thereon. The entire unit is adapted to be placed upon a level table top, desk or other such supporting surface.

It is important when the device of this invention is used, that the disc 15 be statically balanced so that the bubble in the level 16 is centered when the entire unit is supported in a level position prior to use. The disc 15 is calibrated in polar coordinates with two perpendicular center lines X—X and Y—Y indicating the horizontal and vertical axes. In addition, the angular distances starting at the right end of the X—X axis are shown in degrees. To make the device easier to use, the angles in

2

both directions are indicated. If desired, the values of the sine and the cosine of the marked angles may also be shown. A plurality of concentric rings spaced equally from the center to the outer edge of the disc 15 indicate the linear distance from the center out. Each of the rings may be marked with a proportional value. Thus, for example, the fifth ring out from the center in a set of ten rings may be marked "5," or "50," or "500." Each ring is thus labeled to indicate the relative distance of that ring from the center of the disc 15. The outer annular disc 19 is also divided into two sets of angular marks which indicate the angular distances from a zero point in either direction. When using the device of this invention, equal weights are placed at positions which represent both the relative lengths of the vectors being calculated and their angular relationship. This can better be explained by reference to the two problems shown in the drawings.

Considering first FIG. 3, a triangle ABC is shown with the lengths of the sides AB and AC being shown as 86 and 40 respectively. Angle B has a value of 37°. To determine the length of side BC and angles A and C, it is assumed that the side AB lies on the positive X—X axis. A weight 23 is placed on the X—X axis at a distance equivalent to 86, or approximately $\frac{1}{10}$ of the distance between the 8 and 9 circles on the disc 15. A second weight 21, equal in size to the first weight 23, is placed on the disc 15 along the radius which represents 37° in the second quadrant, or 37° clockwise of the negative X—X axis. The effect of the two weights 21 and 23 is to unbalance the disc 15, causing it to tilt until its edge rests on the rim 17. A third weight 22 is placed on the disc 15 on a line which approximately passes through the center 16 and the point at which the disc 15 rests on the rim 17. The weight 22 is then moved about until the disc 15 is completely balanced as shown by the bubble level 16. The distance of the weight 22 from the center, as indicated by the concentric circles, indicates the length of the side CB. In this case it is about 60. The angle A is the angular distance between the negative X—X axis and the radius on which the weight 22 rests. This is approximately 23.75° (more correctly 23° 40'). To determine the value of angle C, the ring 19 is rotated until the angular value of the angle A, namely 23° 40', lies on the radius of the line CA. Angle C is then the reading on the ring 19 which is adjacent the positive end of the X—X axis, or the radius on which the side AB lies. This appears to be approximately 119.25° or 119° 15'. Of course, the disc 15 and the ring 19 are not marked sufficiently well in the illustrative figures of this application to provide the accuracy indicated. But with an instrument having a large diameter and carefully measured markings, good accuracy can be expected.

The sides of triangles necessarily join to form a closed figure, but in the solution of triangles with the instrument of this invention, the sides are represented as lengths of lines from the center of the disc 15. For this reason, the supplement of the known angle is laid-off on the disc 15. This is readily done if one of the sides is placed along a major axis, as the X—X axis. The supplementary angle is then the angular distance from the other end of the same axis. The ring 19 is used to determine the third angle of the triangle when two are already known. Thus, in the example given, the CA represents an angular distance of 37° from the X—X axis. The aligning of the value of angle A with the line CA on disc 15 adds the values of the two angles A and B together and measures the total from one end of the X—X axis. The remaining angle C is the difference between 180° and the sum of angles A and B and is indicated by the point at which the positive side of the X—X axis intersects the ring 19.

In summing a plurality of vectors, a similar procedure is followed. FIG. 5 represents a vector diagram in which

the resultant vector is to be determined. Again, the vectors are related to the X—X and the Y—Y axes and the angles are measured therefrom. In the diagram shown, the three vectors J, K, and L may represent forces being applied to a member which lies at the center O. The vector J represents a force having a value of 10 pounds (or 10 tons) applied to the member O at an angle with the +X—X axis of 30°. The vector K represents a force having a strength of 20 pounds applied to the member O at an angle with the +Y—Y axis of 30° or at an angle from the +X—X axis of 120°. The third vector L represents a force having a strength of 10 pounds applied to the member O at an angle of 45° from the —X—X axis or 225° from the +X—X axis. Since the forces vary by a ratio of two-to-one, the weight representing the vector J is placed on the 10 ring at an angle of 30° from the +X—X axis. The vector K is represented by two weights placed on the 10 ring at an angle of 120° from the +X—X axis. In this manner, the ratio of the forces is maintained, and the device is kept as sensitive as possible. The vector L is represented by one weight on the 10 ring at an angle of 225° from the +X—X axis. Again, the disc 15 is unbalanced by the weights and tilts until the edge rests on the rim 17. The value of the resultant of the three vectors is found by using a pair of weights and moving them over the disc 15 on the same general diameter defined by the center O and the point which rests on the rim 17 until the disc 15 is again balanced. In the example shown, one of the two weights is placed at the 10 ring and the other at a position which is about 7.5 from the center, both on the same radius which is at an angle of about 300° from the +X—X axis. Again, a larger diameter disc more carefully calibrated in smaller units will yield more accurate results.

From the above, it can be seen that the device of this invention demonstrates the effects of vectors upon a system and provides a simple and effective device for calculating vector problems. In addition, the effects of individual vectors, alone and with others, upon a system can be demonstrated by the separate application of individual weights at their proper locations on the disc 15. Therefore, the device of this invention is useful not only for calculation purposes, but also for teaching and demonstration purposes.

The above specification has described a new and improved device for calculating the effects of vectors, vector summations, and many trigonometric problems as well as for demonstrating these problems. It is realized that the above disclosure may indicate to others different ways of utilizing the principles of this invention without departing from the spirit thereof, and it is, therefore, intended that this invention be limited only by the scope of the appended claims.

What is claimed is:

1. A device demonstrating the computation of the vector sum of a plurality of vectors, said device comprising a housing open at one end, a vertically disposed support

member centrally located in said housing, a pivot mounted upon the upper end of said support member, a flat disc supported upon said pivot in a balanced position, said disc being calibrated in distances from its pivot point and in angular distances around its circumference from a zero point, first weights of known value in positions representative of vectors placed upon its upper surface in positions which correspond to the size and direction of said vectors, second weights representative of the resultant and being of known value, said second weights being placed in positions to completely balance the composite effect of said first weights, and means for indicating when a balance is achieved and the values and directions of the resultant.

15 2. A device for illustrating the computation of the value of a resultant of several vectors, said device comprising, a chart calibrated in distances from its center and in degrees displacement about its periphery, means for supporting said chart in a balanced position, first bodies of known weight located on said chart in positions representative of the sizes and directions of each of several vectors to unbalance said chart, and means for indicating the value and direction of the force necessary to rebalance said chart.

20 3. A computer for computing trigonometric problems, said computer comprising, a chart having a point of static balance, said chart being calibrated in distances from said point of balance and angular distances from a prescribed axis, means for supporting said chart at the point of balance, first weights of equal value positioned on said chart at positions representative of the relative sizes and angular positions of known trigonometric quantities, second weights for rebalancing said chart, and means for indicating when said chart is rebalanced after being unbalanced by forces representative of trigonometric quantities applied thereto.

25 4. The computer defined in claim 3 further comprising an annular scale calibrated in degrees of arc and mounted concentric with said chart, and means for rotating said annular scale to indicate the summation of trigonometric angles.

30 5. The computer defined in claim 3 further comprising means rotatably mounted concentric with said chart for indicating the difference between the angular summation of the trigonometric quantities and a known value of angular measurement.
